UNITED STATES PATENT OFFICE

GEORGE T. RONK, OF CEDAR RAPIDS, IOWA, ASSIGNOR TO SPEEDER MACHINERY CORPORATION, OF CEDAR RAPIDS, IOWA, A CORPORATION OF IOWA

REVERSIBLE CABLE DRUM

Application filed June 20, 1927. Serial No. 200,134.

The object of my invention is to provide a reversible drum of simple, durable and inexpensive construction, which may be utilized for operating various kinds of cable controlled devices such as drag line buckets, clam shell and hoisting devices, the drum also being particularly adapted for operating the dipper stick of an excavating bucket.

A further object is to provide a reversible drum which is provided with a suitable driving mechanism designed to be operated in a continuous manner and at a uniform speed in one direction, and to provide in connection therewith means whereby the cable drum may be operated in unison with said driving mechanism, or may be operated in a reverse direction at a higher speed than the said driving device.

A further object is to provide in a reversible cable drum, improved means whereby the drum may be thrown into and out of operation with a driving member and be reversed at a higher speed than the driving member, and in connection therewith to provide means whereby the reversing mechanism for operating the drum may be thrown out of operation.

A further object is to provide in connection with a reversible cable drum, improved means for throwing the drum into operative relation with a driving element, said device being provided with a manually controlled clutching mechanism and a power clutching mechanism so arranged that the power clutching mechanism will be actuated through power derived from the driving element.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved cable drum.

Figure 2 is a vertical, longitudinal sectional view of the same.

Figure 3 is a detail sectional view taken on the line 3-3 of Figure 2.

Figure 4 is a detail sectional view taken on the line 4-4 of Figure 2.

Figure 5 is a detail sectional view taken on the line 5-5 of Figure 2.

Figure 6 is a detail sectional view taken on the line 6-6 of Figure 3, showing the manner in which the reversing mechanism is thrown out of gear; and

Figure 7 is a detail sectional view taken on the line 7-7 of Figure 1.

Referring to the drawings, I have used the reference numeral 10 to indicate frame members on which my device is mounted, said frame members being provided preferably with inwardly projecting brackets 11. Each of the brackets 11 is provided with a detachable block 12 in which is mounted a horizontally arranged shaft 13, said shaft being fixed in said blocks by means of suitable set screws 14 so as to support the shaft rigidly therein.

Rotatively mounted on one end of the shaft 13 is a driving gear 15, which is designed to be continuously operated in one direction in a counter clockwise direction, as illustrated in Figure 3. The gear 15 is provided with a hub 16, on which is rotatively mounted a collar 17, the collar being provided with an annular groove 18 in which are mounted semi-circular clutch members 19. The ends of the members 19 are provided with outwardly extending flanges 20 and 21, the flanges 21 being considerably longer than the flanges 20. The flanges 20 are provided with a screw 22, while the flanges 21 are mounted within a bracket 23, said bracket comprising a pair of spaced, vertically arranged members having their upper ends connected with a bar 24 which is secured to a suitable lug 25 projecting inwardly from one of the frame members 10.

Mounted between the vertical members of the bracket 23 is a cam 26, said cam being designed to engage one of the members 21, the opposite member 21 being designed to rest against a set screw 27. The cam 26 is provided with a horizontally extending arm 28, to which an operating link 29 is pivotally connected. The members 19 are adjusted in such a manner by means of the screws 22 and

27 that the collar 17 will rotate freely within the members 19 when the lever 28 is at its upper limit of movement, permitting the members 21 to be separated, the said members 19 being designed to frictionally grip the collar 17 when the lever 28 is moved downwardly, causing the cam 26 to elevate the lower one of the members 21. This provides means whereby the collar 17 will be 10 slightly rotated relative to the rotating hub in a manner hereinafter more clearly set forth.

The collar 17 is provided with a radially projecting arm 30, the free end of which is 15 provided with a spring 31, one end of the spring being connected to the spoke 32 of the gear 15, a pin 33 being mounted in the arm 30 and projecting inwardly to engage one edge of the spoke 34 and provide means 20 for limiting the movement of the arm 30 through the action of the spring 31.

Supported rigidly on the shaft 13 adjacent to the hub 16 of the gear 15 is a spider 35 having preferably three radially projecting spokes, each of which is provided with a laterally projecting pin, each of said pins being designed to carry a pinion 37. Rotatively and slidably mounted on the hub of the spider 35 is a clutch member 38 having 30 its periphery provided with a cone-shaped clutching surface. The hub of the member 38 is provided with a spur gear 39 designed to mesh with the pinions 37, said gear being rigidly connected to said hub.

35 Supported on the spokes of the gear 15 is an internal gear 40 which is also in mesh with the pinions 37. Rotatively mounted on the shaft 13 is a cable drum 41 having flanges 42 and 43, the flange 43 being provided with a clutch member 44 designed to coat with 40 the clutch member 38. The flange 43 is also provided with a band drum 45 having a clutch band 46, one end of which is secured to a pin 47 projecting inwardly from the gear 15. The other end of the band 46 is connected to a pin 48, said pin being mounted on one end of a lever 49, said lever being pivotally mounted in a bracket 50 secured to one of the spokes of the gear 15. 45 The inner end of the lever 49 is provided with a roller 51 designed to make engagement with a cam 52 formed on the collar 17.

The free end of the band 46 is adjustably connected to the pin 48 by means of a bolt 53, a spring 54 and a bracket 55. A spring 56 is mounted between the hub of the clutch member 38 and the inner end of the drum 41 for yieldably moving the clutch member 38 out of engagement with the clutch member 44 by sliding the drum 41 lengthwise on the shaft 13. The clutch member 44 is brought into engagement with the clutch member 38 by means of a cam device 57 which is rotatively mounted on the shaft 13 and which is designed to coat with the sta-

tionary cam member 58. The cam member 57 is provided with a lever 59 which is provided with a downwardly extending link 60, the lower end of the link 60 being connected to a rock arm 61 mounted on a rock shaft 62. The shaft 62 is also provided with a rock arm 63 extending in the opposite direction from the arm 61 and connected to the lower end of the link 29, the shaft 62 being actuated by means of a hand lever 64.

A large amount of wear and noise may be eliminated by removing the pinions 37 from their coating gears, thus throwing the clutch member 38 out of operative relation with the gear 40. The clutch 38 may then be permitted to rotate with the clutch member 44, or the clutch member 38 may be thrown out of operative relation with the last said clutch member.

The operation of my device is as follows: Assume that the drum 41 is provided with a suitable cable having its free ends operatively connected with a dipper stick in such a manner that as the drum is rotated in one direction the dipper stick will be crowded outwardly, and as it is moved in the opposite direction the dipper stick will be moved inwardly. Or the drum might be provided with a cable adapted to operate a drag bucket or a skimmer bucket, one of the ends of the cable being designed to serve as an out-haul cable, and the other end of the cable as an in-haul cable, and in both cases it will be seen that it is necessary to reverse the rotation of the drum to actuate the buckets. Sometimes it is desired to disconnect the drum from its operating means to cause the buckets to be brought to a standstill.

From the foregoing construction it will be seen that if the pinions 37 are mounted on the pins 36 and the gear 15 is rotated in a counter-clockwise direction, as illustrated in Figure 3, the internal gear 40 will also be rotated, which will cause the pinions 37 to be rotated, which in turn will rotate the gear 39 in the opposite direction from the internal gear 40 and at a higher speed. This in turn will cause the clutch member 38 to be rotated in the opposite direction from the gear 15. Then it will be seen that if the lever 64 is grasped and the shaft 62 rocked in a counter-clockwise direction, as illustrated in Figure 3, the link 60 will be moved downwardly, causing the drum 41 to be moved to the left, as viewed in Figure 2, and the clutch member 44 to engage the clutch member 38, which will cause the drum 41 to be rotated in the opposite direction from the gear 15 and at a higher speed.

If the shaft 62 is operated in a clockwise direction, then the link 60 will be elevated and the drum 41 moved axially and the clutch members 38 and 44 caused to disengage each other. The link 29 will at the same time be moved downwardly, causing the cam 26 to

squeeze the members 21 together, thereby causing the members 19 to frictionally engage the collar 17, which is being rotated in unison with the gear 15 through the spring 31. This frictional engagement between the members 19 and 17 will cause the movement of the collar 17 to be retarded relative to the movement of the gear 15, and the cam 52 to engage the roller 51 of the arm 49, causing the inner end of said arm to be moved outwardly and the outer end of said arm to be moved, so that tension will be applied to the band 46, which will be brought to engagement with the drum 45, causing the cable drum 41 and the gear 15 to be locked to operate in unison, the drum 41 rotating at the same speed and in the same direction as the gear 15.

This provides means whereby powerful clutching action may be imparted between the band 46 and the drum 45 with a comparatively small amount of energy being imparted to the lever 64, and provides means whereby a small amount of manual energy is required to operate what I shall term the power clutch member comprising the band 46, the lever 49 and the power driven cam 62. The members 19 and 21, together with the cam 26 and the lever 28, constitute what I shall term the manually controlled clutch member.

Sometimes it is desirable to operate the drum in one direction only, in which case the pinions 37 are removed in the manner hereinbefore described, thereby eliminating the wear between the said pinions and their co-acting gears, as well as the noise created thereby, and also the wear between the clutch member 38 and the hub of the spider 35.

Thus it will be seen I have provided a reversible cable drum which is particularly adapted to be used on that type of an excavating machine having a boom on which are mounted the various kinds of excavating buckets, so that the said drum may be utilized for operating the various devices, and which is very compact, especially in length, as the stationary spider is mounted within the flange of the clutch member and also the internal and spur gears, the clutch members for setting the drum and driving gear in fixed relation being mounted within the flange of the gears.

This compact arrangement is a very desirable feature in a device of this kind, inasmuch as the width of the entire excavating machine may be materially thereby decreased, decreasing the cost of the machine as well as the weight.

Another advantage of my device consists in being able to easily and quickly throw the reversing mechanism out of operation when so desired.

Another advantage of the device lies in the easier manner in which the controlling devices may be operated. This is also a very desirable feature, as in excavating machines

of this class quite a large number of lever devices have to be operated.

Another advantage of my device lies in providing means whereby the drum may be operated in a reverse direction at a higher speed than the driving gear. This is especially desirable when the device is used in connection with a dipper stick, it being desirable to connect the crowd cable on the drum in such a manner that the crowd action of the devices takes place when the drum and gear are connected directly. This is at the time when the heavy load is being carried by the driving gear, thereby relieving the strain from the reverse gears, it being desirable to rake the bucket in at a considerably higher speed for the purpose of cutting down the operating time as well as imparting momentum to the bucket for throwing it into operative position and to eliminate the necessity of an extra back line.

I claim as my invention:

1. A reversible winch comprising a support, a shaft fixed therein, a driving gear rotatively mounted on said support, having an internal gear secured thereto, a spider fixed to said shaft having laterally projecting pins, a pinion for each of said pins in mesh with said internal gear, a clutch member rotatively mounted about said shaft and adjacent to said spider, said clutch member being provided with a spur gear also in mesh with said pinions, the clutch member being mounted adjacent to the outer ends of said pins for retaining said pinions in position thereon, said clutch member and said spur gear being slidably mounted on said shaft, a second clutch member designed to engage the first said clutch member upon being moved inwardly, yieldable means between said clutch members for throwing them out of engagement, and means for imparting inward movement to said second clutch member to cause engagement between said clutch members, the clutches being adapted to permit outward movement to cause said spur gear to disengage said pinions, and to provide clearance between the pinion retaining member of said clutch member and said pinion pins for the removal of said pinions.

2. A reversible winch comprising a support, a shaft fixed therein, a driving gear rotatively mounted on said support, having an internal gear secured thereto, a spider fixed to said shaft having laterally projecting pins, a pinion for each of said pins in mesh with said internal gear, a clutch member rotatively mounted about said shaft and adjacent to said spider, said clutch member being provided with a spur gear also in mesh with said pinions, the clutch member being mounted adjacent to the outer ends of said pins for retaining said pinions in position thereon, said clutch member and said spur gear being slidably mounted on said shaft,

a second clutch member designed to engage the first said clutch member upon being moved inwardly, yieldable means between said clutch members for throwing them out of engagement, means for imparting inward movement to said second clutch member to cause engagement between said clutch members, the clutches being adapted to permit outward movement to cause said spur gear 10 to disengage said pinions, and to provide clearance between the pinion retaining member of said clutch member and said pinion pins for the removal of said pinions, a drum, and means for locking said driving gear and 15 said drum to operate in unison when the said clutch members are disengaged.

3. A reversible winch comprising a support, a shaft fixed therein, a driving gear rotatively mounted on said shaft, having an 20 internal gear secured thereto, a spider fixed to said shaft having laterally projecting pins, a pinion for each of said pins in mesh with said internal gear, a clutch member mounted to rotate about said shaft and adjacent 25 to said spider, said clutch member being provided with a spur gear also in mesh with said pinions, the clutch member being mounted adjacent to the outer ends of said pins for retaining said pinions in position 30 thereon, said clutch member and said spur gear being slidably mounted on said shaft, a second clutch member designed to engage the first said clutch member upon being moved inwardly, yieldable means between 35 said clutch members for throwing them out of engagement, means for imparting inward movement to said second clutch member to cause engagement between said clutch members, the last said means being adapted to 40 permit outward movement of said clutch member to cause said spur gear to disengage said pinions, and to provide clearance between the pinion retaining member of said clutch member and said pinion pins for the 45 removal of said pinions, a drum, means for locking said driving gear and said drum to operate in unison when the said clutch members are disengaged, means operated by said driving gear for actuating the last said 50 means, and manually controlled means for actuating said gear operating means.

4. A reversible winch comprising a support, a shaft fixed therein, a driving member rotatively mounted on said shaft, said 55 driving member including an internal gear, a spider fixed to said shaft having a laterally and inwardly projecting pinion supporting pin, a pinion for said pin in mesh with said internal gear, a clutch supporting 60 element mounted to rotate about said shaft and adjacent to the free end of said pin, said clutch element being provided with a spur gear within said internal gear and in mesh with said pinion, a cable drum rotat- 65 tively mounted on said shaft, having a clutch

member to coact with the first said clutch member, and means for causing said clutch members to be brought into clutching engagement, the clutch supporting element being adapted to slide outwardly from the free end of said pin to permit the pinion to be removed therefrom. 70

5. A reversible winch comprising a support, a shaft fixed therein, a driving member rotatively mounted on said shaft, said driving member including an internal gear, a spider fixed to said shaft having a laterally and inwardly projecting pinion supporting pin, a pinion for said pin in mesh with said internal gear, a clutch supporting element mounted to rotate about said shaft and adjacent to the free end of said pin, said clutch element being provided with a spur gear within said internal gear and in mesh with said pinion, a cable drum rotatively mounted on said shaft, having a clutch member to coact with the first said clutch member, means for causing said clutch members to be brought into clutching engagement, the clutch supporting element being adapted to slide outwardly from the free end of said pin to permit the pinion to be removed therefrom, and means carried by said driving element for causing said cable drum and said driving element to be rotated in unison when the said clutch devices are out of engagement. 80

6. A reversible winch comprising a support, a shaft fixed therein, a driving member rotatively mounted on said shaft, said driving member including an internal gear, a spider fixed to said shaft having a laterally and inwardly projecting pinion supporting pin, a pinion for said pin in mesh with said internal gear, a clutch supporting element mounted to rotate about said shaft and adjacent to the free end of said pin, said clutch element being provided with a spur gear within said internal gear and in mesh with said pinion, a cable drum rotatively mounted on said shaft having a clutch member to coact with the first said clutch member, means for causing said clutch members to be brought into clutching engagement, and means carried by said driving element for causing said cable drum and said driving element to be rotated in unison when said clutch devices are out of engagement. 90
